(57) **CLAIM**

The ornamental design for a straw lid as shown and described.

DESCRIPTION

FIG. 1 is a perspective view of a straw lid, showing my new design in an open state;

FIG. 2 is the second perspective view thereof;

FIG. 3 is the third perspective view thereof;

FIG. 4 is a front elevational view thereof;

FIG. 5 is a rear elevational view thereof;

FIG. 6 is a left elevational view thereof, the right side view being a mirror image of FIG. 6;

FIG. 7 is a top side view thereof;

FIG. 8 is a bottom plan view thereof;

FIG. 9 is an enlarged view of FIG. 1;

FIG. 10 is another enlarged view of FIG. 1;

FIG. 11 is a perspective view of the straw lid, showing my new design in a closed state; and,

FIG. 12 is another perspective view thereof.

The broken lines in the figures are for the purposes of illustrating portions of the straw lid, which form no part of the claimed design.

1 Claim, 11 Drawing Sheets
